(57) **CLAIM**

The ornamental design for hockey puck card stand device, as shown and described.

DESCRIPTION

FIG. 1 is a perspective view of a hockey puck card stand device, showing my new design; the broken lines are for environmental purposes only and form no part of the claimed design.

FIG. 2 is a front view of the hockey puck card stand device of FIG. 1;

FIG. 3 is a side view of the hockey puck card stand device of FIG. 1;

FIG. 4 is a top view of the hockey puck card stand device of FIG. 1; and,

FIG. 5 is a bottom view of the hockey puck card stand device of FIG. 1.
